[57] ABSTRACT

An X-ray diffraction apparatus comprising means for rotating a specimen in the path of an X-ray beam and means for rotating a diffraction slit simultaneously with the specimen but at a lower angular velocity, so that the X-ray irradiated portion of the specimen remains substantially constant in size during such rotation.

X-RAY DIFFRACTION APPARATUS

BACKGROUND OF THE INVENTION

The present invention relates to an x-ray diffractometer apparatus. 5

Generally, an X-ray diffraction apparatus comprises a source of X-rays and divergence slit through which X-rays pass toward a specimen that is to be analyzed by X-ray diffraction, the divergence slit serving to form an X-ray beam having desired geometric characteristics. During X-ray diffraction analysis the specimen being investigated is rotated about an axis lying in its upper flat surface, to cause the X-ray beam to impinge upon the specimen at various angles, the rotation being so that the angle (θ) between the specimen surface and a line drawn from the X-ray source to the center of the irradiated portion thereof ranges between 0° and 90°. 15

During such X-ray diffraction analysis the divergence slit remains stationary, so that, because of the rotation of the specimen with respect to the divergence slit and as a result of geometric considerations, the area of the specimen irradiated by the X-ray beam varies between a relatively small amount when the value of θ is high (e.g., 80°) and a relatively large amount when the value of θ is low (e.g., 10°). Such variation of the irradiate area is highly undesirable because of numerous adverse effects on the accuracy and reliability of the analysis. 20

To cope with such variation of the irradiated area, the prior art has resorted to using, during each diffraction analysis, stationary divergence slits of various fixed sizes, with larger slit openings being employed for large θ values and smaller slit openings being employed for smaller θ values, thereby tending to equalize the irradiated area of the specimen as it is rotated over the range of θ values. Such a practice is undesirable because interchanging the divergence slits is a time-consuming process and because it is necessary to have available a number of such divergence slits of various sizes, which can be an expensive proposition, and even more important, because interchaning the divergence slits still results in a significant amount of variation in the X-ray 25 irradiated of the specimen. 45

While the prior art has proposed various method for controlling the irradiated specimen area (see, for example, M. Loisel, "Bulletin de la Societe Francaise de Ceramique," Issue No. 90, Jan. March 1971, pp. 55 et seq.) such have not been fully desirable nor useful, by reason of, inter alia, their operating on a gross scale that is insufficiently precise for the very important small angular values (θ) of specimen orientation. 50

The present invention overcomes the above shortcomings by providing an apparatus permitting the rotation of the divergence slit in conjunction with the rotation of the X-ray irradiated specimen, whereby the dimensions of the X-ray irradiated portion of the specimen remain substantially constant during the rotation of the specimen. In a preferred embodiment, the divergence slit is connected to a structural element linked with a second structural element connected to the specimen such that the divergence slit rotates at a lower angular speed than the specimen such that the X-radiation is cut off from the specimen when the θ value reaches zero. 55

DESCRIPTION OF THE DRAWINGS

FIG. 1 is a schematic representation of a prior art X-ray diffraction apparatus. 5

FIG. 2 is an isometric view of the X-ray diffraction apparatus of the present invention. 10

FIG. 3 is a schematic representation depicting a feature of the present invention. 15

FIG. 4 is a fragmentary sectional elevation view of a diffraction slit of the type employed in the present invention. 20

FIG. 5 is a number of curves depicting results obtained with the present invention. 25

THE PREFERRED EMBODIMENT

FIG. 1 depicts the situation in the prior art where the X-ray diffraction specimen 10 is rotated with respect to a stationary divergence slit 11 through which there passes X-radiation 12 from a source 13. When the specimen 10 is acutely disposed (i.e., θ_A is less than 90°) to an imaginary line 14 extending between the X-ray source and the center of the irradiated portion of the specimen, the portion of the specimen impinged by the X-radiation has a dimension S_A , whereas the impinged portion dimension S_B when when θ_B equals 90° (shown in broken lines) is substantially less than S_A . Such deviations in the dimensions of the X-radiation impinged portion of the specimen are unsatisfactory, as mentioned above. 30

FIG. 2 depicts a portion of the X-ray diffraction apparatus 20 in accordance with the present invention, containing an X-ray line source 22, as so-called "Soller slit" assembly 24, a rotatable divergence slit 25 mounted via a shaft to a cog wheel 26, a specimen holder 27 connected to a second cog wheel 28, the X-ray diffraction analysis specimen 29 which is mounted on the holder 27, the second cog wheel 28 being driven by a drive shaft 30 whose rotation speed 35 is co-ordinated with the rotation speed of the goniometer (not shown) used with the diffraction apparatus, a mechanical linking means 31 (i.e., cog belt) linking the cog wheels 26 and 28, and a receiving slit 32, a Soller slit 33 and an anti-scatter slit 34 all (i.e., 32, 33, and 34) located between the specimen and the detector 35. It is essential that the divergence slit cog wheel 26 include a number of teeth greater than that of the specimen cog wheel 28 (i.e., a slit cog to specimen cog tooth ratio greater than 1) so that the former rotates at a lower angular speed (i.e., provides a smaller corresponding angular displacement) than the former, it being especially preferred that the tooth ratios of these cog wheels be adjusted such that the beam be cut off from the specimen upon the θ value reaching zero degrees and that the slit plane and the irradiated specimen surface be substantially parallel when θ is 90°. 40

By way of the explanation, reference is made to FIG. 3 where there are depicted the divergence slit cog wheel 26 and the specimen cog wheel 28 that are linked by a mechanical coupling (i.e., cog belt 31). The specimen cog wheel 28 has a certain number, N , of teeth (not shown) while the divergence slit cog wheel 26 has a larger number, N' , of cog teeth (not shown). When the specimen cog wheel 28 is rotated by a certain angular displacement, the slit cog wheel 26, too, rotates by a given angular displacement, the total angular displacement, θ' of the slit cog wheel 26 being determined 45 50 55 60 65 66

from the following relationship based on geometric considerations:

$$\theta' = N/N' \theta + \theta_0', \quad (\text{Eq. 1})$$

where θ is the angular displacement of the specimen cog wheel 28 and θ_0' is the initial angular displacement of the slit cog wheel 26 with respect to specimen cog wheel 28 (i.e., the initial angular disposition of the slit with respect to the specimen irradiated surface). By virtue of the diffraction slits having a finite thickness, the beam is cut off from the specimen before θ' reaches zero, so that the geometry of the diffraction slit should be considered in order that X-ray beam extinction occur (i.e., the beam is cut off from the specimen), under optimal conditions, when θ equals exactly 0° . Therefore, assuming a diffraction slit having substantially the geometry shown in FIG. 4, wherein r represents the radius of the cylindrical slit-defining portion 40 defining the slit opening 42, w represents the width of the opening 42 and t represents the thickness of the slit-defining body 43. While the slit is shown with cylindrical slit defining portions, other geometries can be used, e.g., rectangular slit-defining portions. An imaginary line from and tangent to one face 44 of the slit-defining portion 40, to and tangent to the opposite such face 46 forms an angle, ϵ , with the slitdefining body 43. Therefore, the following expressions can be derived. Where

$$k = r + (w/2)$$

(Eq. 2)

the extinction, or beam cut off, angle, ϵ , can be determined by the following expressions:

$$\sin \epsilon = r/k \text{ so that } \epsilon = \sin^{-1}(r/k) \quad (\text{Eq. 3})$$

Optimally, X-ray beam extinction occurs exactly when $\theta = 0$, so that it is preferred that $\theta' = \epsilon$ at $\theta = 0$. Substituting these conditions into Equation 2 under this optimal condition results in the expression:

$$\theta' = N/N' \theta + \epsilon \quad (\text{Eq. 4})$$

(Eq. 4)

If θ_0' is greater than ϵ , the length (S) of the X-ray irradiated portion of the specimen increases rapidly as θ approaches zero, whereas a value of θ_0' less than ϵ results in a decrease of the irradiated portion lengths as θ approaches zero. The latter situation (i.e., $\theta_0' < \epsilon$) results in premature extinction, in that the irradiated portion length is zero at some θ value greater than zero.

It is further optimal that $\theta' = 90^\circ$ when $\theta = 90^\circ$, so that there is achieved an irradiated specimen portion of maximum length for values of θ approaching 90° .

Re-writing Equation 4 to satisfy this second optimal condition

$$\theta' = 90^\circ = N/N' (90) + \epsilon$$

(Eq. 5)

$$N/N' = 90 - \epsilon/90$$

(Eq. 6)

Equation 6 establishes the condition that must be met by numbers N and N' of cog wheel teeth. N and N' must also, of course, be integers. In practice, one picks values that most closely satisfy Equation 6.

EXAMPLE 1

Using a diffraction slit having a cylindrical slit-defining body with a radius r of 0.60 mm, a body thickness t of 1.20 mm, and a slit opening width w of 5.00 mm, the value k of the diffraction slit is 3.10 mm and the extinction angle, ϵ , is determined from Equation 3 to be $11^\circ 10'$. Therefore, when $\theta = 0$, θ_0' should optimally be $11^\circ 10'$ and, as a second optimal condition, when $\theta = 90^\circ$, θ' should also be 90° . From Equation 6, the cog tooth number ratio, N/N' for the specimen and slit cog wheels should be about 79:90 for maintaining an irradiated specimen portion of substantially constant dimensions, this being done automatically during the specimen rotation.

Using the values $\theta_0' = 11^\circ 10'$ feet and an $N:N'$ tooth number ratio of 79:90 and assuming a distance of 172.00 mm, between the center of the irradiated specimen portion and the X-ray source and a distance of 72.00 mm between the X-ray source and the slit center, the length, S , of the irradiated portion of the specimen was calculated for θ values over the range of 0° to 90° , the resulting S values being shown as Curve I in FIG. 5. In this situation θ' equals 90° when θ is 90° . With these same values, except for $\theta_0' = 11^\circ 10'$ feet, the length S of the irradiated portion of the specimen was calculated for θ values over the range of 0° to 90° , the resulting S values being shown by Curve II in FIG. 5. The significant improvement provided by setting θ_0' at exactly the value of ϵ is seen from the comparison of these curves, the length, S , of the irradiated portion in Curve II not exhibiting the relatively sharp drop for the S value for very low θ values i.e., about $\theta = 5^\circ$. With these same values, except for θ_0' and a tooth ratio $N:N'$ of 90:90 for the slit and specimen cog wheels, the S value was calculated over the range of $\theta = 0$ to 90° , the results being depicted as Curve III in FIG. 5. The significant improvement provided by the present invention is seen from the comparison of these Curves, the length, S , of the irradiated portion remaining substantially constant over substantially all of the range between $\theta = 0$ to $\theta = 90^\circ$ (Curves I and II) when the slit cog: specimen cog tooth ratio is greater than 1 (i.e., 90:79), whereas, as shown by Curve III, the length, S drops dramatically for θ values below about $\theta = 50^\circ$ and is zero at about $\theta = 12^\circ$ for the situation where the cog wheels have the same number of teeth (i.e. $N = N'$).

Thus, the present invention permits achieving an irradiated specimen portion of substantially constant dimensions over the rotation range for analyzed specimen. While setting θ_0' at exactly ϵ leads to a deviation of θ' from 90° when θ equals 90° , it is felt to be more preferable to set θ_0' at exactly the value of the extinction angle, ϵ , notwithstanding the fact that θ' will not equal θ at $\theta = 90^\circ$, in order to avoid the drop in S values about θ equals 5° and less.

I claim:

- 60 1. An X-ray diffraction apparatus comprising:
  - a. a source of X-rays;
  - b. means for holding an X-ray diffraction specimen in the path of said X-ray beam such that a portion of said specimen can be impinged by said beam;
  - c. means for rotating said specimen at a first angular velocity from a first position to a second position;

- d. a diffraction slit disposed between said specimen and said source such that said X-rays pass through the opening of said slit;
- e. means for rotating said diffraction slit simultaneously with the specimen, said diffraction slit being so rotated at a second angular velocity lower than said first angular velocity; and
- f. means for measuring the intensity of X-rays reflected from said specimen, whereby said irradiated portion remains substantially constant throughout the rotation of said specimen.

2. An X-ray diffraction apparatus as defined in claim 1, wherein at said first position said position is substantially perpendicular to an imaginary line extending from said X-ray source to the center of said portion and said second position said portion is substantially parallel to said imaginary lines and said diffraction slit is rotated between third and fourth positions, said diffraction on slit at said third position being substantially parallel to said specimen at said third position being substantially parallel to said specimen at said first position and at said fourth position being obliquely disposed to said specimen at said second position.

3. An X-ray diffraction apparatus as defined in claim 1, wherein said means for rotating said specimen comprises a first cog wheel and said means for rotating said diffraction slit comprises a second cog wheel driven by said first cog wheel.

4. An X-ray diffraction apparatus as defined in claim 3, wherein the gear ratio of said first cog wheel to said second gear wheel is less than one.

5. An X-ray diffraction apparatus as defined in claim 4, wherein said first gear wheel is mechanically linked to and drives said second gear wheel.

- 6. An X-ray diffraction apparatus as defined in claim 3, wherein the angular displacement θ' of said second gear wheel is determinable from the expression:

$$\theta' = N/N' \theta + \epsilon,$$

where N and N' are the teeth numbers for said first and second gear wheels, respectively;

θ is the angular displacement of said first gear wheel; and
 ϵ is the angular orientation of said second gear wheel when said beam is cut off from said specimen located at said second position.

7. A method of operating an X-ray diffraction apparatus comprising the steps of:

- a. providing an X-ray beam source;
- b. providing an X-ray diffraction specimen disposed at an angle of substantially zero degrees with respect to said X-ray beam;
- c. providing an X-ray diffraction slit between the source of said beam and said specimen, said diffraction slit being disposed at substantially the extinction angle thereof when said specimen is disposed at 0° with respect to said beam, said specimen being rotatable over a range of said angles of from zero to about 90° and said slit being rotatable at a lower angular velocity than said specimen and over an angular range extending from said extinction angle to about 90° ;
- d. irradiating said specimen with said X-ray beam and simultaneously rotating said specimen and said slit over said ranges of angles; and
- e. measuring the intensity of X-rays reflected from said specimen.
